ROLLED-SHEET TEARING MEANS

Filed Dec. 9, 1957

INVENTOR.
Harold Warp,
BY Schneider, Ferguson,
Bundy & Ferguson Attest.

1**3,082,922****ROLLED-SHEET TEARING MEANS**

Harold Warp, Chicago, Ill., assignor to Flex-O-Glass, Inc., a corporation of Illinois
Filed Dec. 9, 1957, Ser. No. 701,606
2 Claims. (Cl. 225—19)

This invention relates to a tearing means and, in particular, to a tearing means for use in a rolled-sheet dispenser.

Known means for dispensing rolled-sheet material, such as waxed paper, plastics, metal foil, etc., comprise a container or housing adapted to receive the roll therein and having an elongated opening through which the end of the rolled-sheet is drawn to be dispensed. To facilitate the tearing of the sheet end from the remainder of the rolled-sheet, one edge of the opening conventionally is toothed. A disadvantage arises in the presently known dispensers, in that once the end portion is torn from the remainder of the roll, it is difficult to manipulate the remainder portion so that the end thereof may be grasped and withdrawn from the housing to be torn from the roll in a subsequent dispensing operation.

The principal object of this invention is to provide a new and improved means for tearing the end portion of a rolled-sheet material which permits the end portion of the remaining rolled-sheet to be grasped readily for a subsequent dispensing operation.

Another object of the invention is to provide a sheet tearing means for use in a dispenser having a housing adapted to receive the rolled-sheet material, which tearing means comprises an outwardly projecting wall extending from the housing a distance substantially greater than the thickness of the person's finger tips and having an outer edge provided with a plurality of sheet tearing teeth, whereby a substantial portion of the remaining sheet material is arranged for ready grasping by the user's fingers.

Still another object is to provide such a tearing means having such a first wall projecting outwardly from the housing and provided with a toothed outer edge and a second wall facially juxtaposed to and substantially coterminous with the first wall, the second wall being provided with a smooth outer edge defining a guard adjacent the tips of the teeth of the first wall to preclude injury to the user's fingers by the teeth.

A still further object is to provide such a tearing means wherein each of said walls is provided with an opening adjacent the opening of the other wall permitting the insertion of a user's fingers therethrough to engage an end portion of the sheet material disposed between the walls.

Yet another object is to provide such a sheet tearing means having a wall projecting from the housing and provided along its outer edge with a plurality of sheet tearing teeth, the wall further being provided with a plurality of reinforcing ribs.

Other features and advantages of this invention will be apparent from the following description taken in connection with the accompanying drawings wherein:

FIG. 1 is a perspective view of a sheet tearing means embodying the invention, the housing on which the sheet tearing means is provided being shown in dotted lines, and a sheet end portion being shown associated with the tearing means for a dispensing operation;

FIG. 2 is a front elevation of the sheet tearing means with portions thereof broken away;

FIG. 3 is an end elevation thereof; and

FIG. 4 is an end elevation of a modified form of sheet tearing means.

In the exemplary embodiment of the invention, as disclosed in FIGS. 1 through 3 of the drawings, a sheet tearing means generally designated 10 is shown to be associated with a container or housing 11 adapted to receive

2

a roll of sheet material 12. To dispense a desired portion of rolled sheet material 12, an end portion 13 thereof is withdrawn from housing 11 to be torn therefrom by means of tearing means 10. Tearing means 10 is arranged in a novel manner so that when end portion 13 has been separated from the rolled-sheet 12, a remaining end portion 14 of the rolled-sheet extends from housing 11 for ready grasping by the user's fingers, thereby to facilitate withdrawal of end portion 14 for a subsequent dispensing operation.

More specifically, tearing means 10 comprises a first wall 15 projecting outwardly from the housing a substantial distance. Wall 15 is provided, along its outer edge, with a plurality of teeth 16. A second wall 17 is provided to project outwardly from the housing facially juxtaposed to and substantially coterminous with first wall 15. The outer edge 18 of second wall 17 is preferably smooth and defines a guard extending adjacent teeth 16 to preclude injurious contact of the user's fingers with the teeth tips.

As indicated above, in the instant invention, the projection of walls 15 and 17 from housing 11 is substantial. It is preferred that this extension be substantially greater than the thickness of a person's finger tips, and a construction found to function very well in dispensing material such as plastic sheeting is one wherein the teeth 16 have a depth of approximately $\frac{1}{8}$ " and the projection of wall 15 from the housing to the teeth is approximately $\frac{3}{4}$ ". The corresponding extension of second wall 17 from the housing is, thus, approximately $\frac{7}{8}$ ". With a tearing means 10 of such construction, it will be seen that remaining end portion 14 of the sheet material extends outwardly from housing 11 substantially $\frac{7}{8}$ ", or a distance substantially greater than the thickness of a person's finger tips.

To permit the engagement of the user's finger tips with the projecting end portion 14, each of walls 15 and 17 is provided with at least one opening through which the user's fingers may be extended into engagement with the sheet portion 14. In the illustrated embodiment, first wall 15 is provided with a pair of such openings 19 and second wall 17 is provided with one such opening 20. Openings 19 and 20 are preferably adjacent one another and, as best seen in FIG. 2, openings 19 may be spaced a short distance on opposite sides of opening 20. Thus, for example, the user may insert the tip of his thumb through opening 20 and the tip of his forefinger and middle finger through spaced openings 19 to engage, on opposite sides, end portion 14 of the rolled-sheet. With sheet portion 14 thus effectively clamped between the user's fingers, sheet portion 14 may be moved outwardly beyond the outer edges of walls 15 and 17 by a movement of the finger tips through openings 19 and 20 in a direction away from housing 11. The portion of the rolled-sheet brought outwardly from the outer edges of walls 15 and 17 may then be grasped and a continued withdrawal of the sheet material from the housing effected until the desired end portion 13 is withdrawn from the housing beyond teeth 16. It should be noted that when end portion 13 is severed from the remainder of the rolled-sheet by being drawn across teeth 16, a new remaining end portion 14 is automatically disposed between walls 15 and 17 so that this new remaining end portion 14 may be manipulated by the user's fingers through openings 19 and 20 in the manner described above when desired.

In FIG. 4 is shown a modified form of tearing means, generally designated 30. Tearing means 30 is similar to tearing means 10 in that it comprises a sheet tearing means which projects substantially from the housing in which the rolled-sheet is retained so that subsequent to a dispensing or tearing operation, a substantial portion of the remaining rolled-sheet is extended from the housing for

ready grasping by the user in a subsequent dispensing operation. More specifically, sheet tearing means 30 comprises a wall 31 projecting outwardly from the housing 32 a distance substantially greater than the thickness of a person's finger tips. The outer edge of wall 31 is provided with a plurality of sheet tearing teeth 33 similar to teeth 16 of sheet tearing means 10. In the illustrated embodiment the projection of wall 31 between housing 32 and teeth 33 is approximately $\frac{3}{4}$ ".

Wall 31 is preferably relatively thin to facilitate the tearing action of teeth 33 against the sheet material. I have found that with such a thin wall having such an extended projection from housing 32, it is desirable to effect a reinforcing thereof to preclude a yielding of the wall when the sheet material is drawn across teeth 33 which may result in an improper tearing operation. For this purpose, one or more reinforcing ribs, such as ribs 34, may be formed in wall 31 extending in a direction generally away from the housing 32. To effect a longitudinal reinforcing of the wall, one or more ribs 35 may be provided extending transversely to the direction of the extent of wall 31 away from housing 32.

While I have shown and described certain embodiments of my invention, it is to be understood that it is capable of many modifications. Changes, therefore, in the construction and arrangement may be made without departing from the spirit and scope of the invention as defined in the appended claims.

I claim:

1. For use in a dispenser having a housing for receiving a roll of sheet material, means for tearing an end portion of the sheet material drawn from the roll and out-

wardly from the housing, said means comprising: a first wall arranged to project outwardly from the housing and provided along its outer edge with a plurality of outwardly projecting teeth, the outward projection of the wall being at least the thickness of an average person's finger tip; and a second wall arranged to project outwardly from the housing facially juxtaposed and spaced from the first wall by the thickness of the sheet end therebetween substantially coterminous with the first wall and provided with a smooth outer edge defining a guard adjacent the tips of the teeth of said first wall to preclude injury to a user's fingers by said teeth, each wall being provided with an opening disaligned with the opening of the other wall permitting the insertion of an opposed pair of the user's fingers respectively therethrough to engage an end portion of the sheet material disposed between said walls and permit mutually opposite urging of the walls tending to increase the spacing therebetween.

2. The tearing means of claim 1 wherein one wall is provided with a single opening and the other wall is provided with a pair of openings at opposite sides of the opening of the first wall.
